UNITED STATES PATENT OFFICE

HOWARD E. BLOOD, OF DETROIT, MICHIGAN, ASSIGNEE TO NORGE CORPORATION, A CORPORATION OF MICHIGAN

ELECTRIC REFRIGERATOR ASSEMBLY

Application filed May 16, 1928. Serial No. 278,250.

This invention relates to mechanical refrigeration as applied as a unit in individual refrigerator boxes, with particular reference to the domestic or household type of electric refrigerating apparatus.

It is an object of this invention to provide a compact and readily removable electric refrigerating apparatus that is completely and permanently assembled with its evaporator or freezer tank and removable as a completely operative unit. I am aware that domestic or household type of refrigerators have been proposed wherein the compressor and condenser unit has been mounted in the bottom of the refrigerator box, but heretofore the mechanism mentioned has had to be drained or sealed up and disconnected from the freezer tank before it can be removed from the refrigerator or otherwise exposed for convenient servicing. In order to overcome these objections, I have mounted the freezer tank on self-supporting framework also carrying the compressor and condenser, the various parts being permanently joined together as an operative unit before placing in the refrigerator proper, so that the initial factory test of the unit so formed will not be liable to be vitiated by the subsequent assembly of the unit into the refrigerating box. Thus, many chances of error in final assembly and future troubles resulting therefrom are eliminated, and in the event that service is required, the entire unit can be removed from the box as an operative assembly, and if necessary, replaced by a new unit rather than be torn down on the spot where repair facilities are limited to the capacity of the mechanic's hand bag.

Other and further important objects of this invention will be apparent from the disclosures in the following description, which sets forth the preferred form of my invention.

This invention (in a preferred form) is illustrated in the drawings and hereinafter more fully described.

On the drawings:

Figure 1 is a front elevation of a refrigerator including refrigeration apparatus embodying the features of this invention.

Figure 2 is a vertical section on the line II-II of Figure 1 with parts shown in elevation.

As shown on the drawings:

A refrigerator cabinet or box of the metal clad type has been chosen for illustrative purposes, such a box comprising a refrigerating compartment 10 surrounded by insulated walls comprising a top 11, rear wall 12, sides 13 and bottom 14; the front 15 having a substantially full opening for a door, (not shown), to render the interior easily accessible.

The refrigerating compartment as a whole is supported at a convenient distance above the floor line by side wall extensions 16 which need not be of an insulated character. These side walls 16 together with a base 17 define a machinery compartment 18 below the refrigerator proper. This compartment 18 is normally closed in front by the usual louvered door, which has been omitted from the drawings, for clearness in the presentation of the structure most pertinent to the present invention.

A freezer tank 20 embodying the evaporator or expansion unit of a mechanical refrigerating apparatus, is positioned in either upper corner of the refrigerator compartment 10. In the present invention, a stepped opening 21, large enough to admit the tank 20, is formed in the rear wall 12 and is closed by a flush closure 22 having stepped or overlapping edges 23 engaging a gasket 24. The tank 20 is provided with mounting brackets 25 engaged by nuts 26 adjustably secured on studs 27 carried by the closure 22, so that the freezer tank 20 and closure 22 are thus assembled together as a unit.

The closure 22 is in turn mounted on an upright channel member 28 extending downwardly to the base of the refrigerator, this member 28 being detachably secured in any suitable manner to the rear wall 12 of the refrigerator.

This member 28 is in effect hung on the rear wall of the refrigerator and its lower end 29 is provided with an outstanding foot 30 projecting into the machinery compartment. This foot is provided largely to pro-

vide stability to the assembly presently to be described when the entire unit is removed from the refrigerator as a whole. A bracket 31 is also provided projecting into the machinery compartment near the top thereof to receive pins 32 passing through ears 33 formed on a dome-like casing 34 which comprises a self-contained motor and refrigerant compressor unit. The casing 34 is thus hung 10 from the bracket 31 and thus forms a unit with the upright member 28 and the freezer tank 20.

A forwardly projecting shelf 35 is preferably attached to the casing 34, although it 15 may be formed as part of the foot 30, to support a radiator 36 forming both a condenser for the refrigerant and an oil cooler for the lubricant in the casing 34. A small fan 37 is also mounted on the shelf to draw air 20 through the radiator, and in Figure 1 a control box 38 is also shown as carried by the shelf.

The refrigerant piping shown comprises a connection 40 from the casing to the radiator for the hot compressed refrigerant, a connection 41 from the radiator to the freezer tank for condensed refrigerant, and a return connection 42 from the tank to the suction intake at the bottom 43 of the casing 34. The 30 pipes 41 and 42 are led up in the channel in the upright member 28 and are protected thereby as well as by a cover 44 applied over the channel opening. Adjacent the freezer tanks the pipes are led through a common 35 aperture 45 in the closure 22. The oil cooling circulation comprises a pipe 46 leading from the bottom section 43 to a special section 47 of the radiator and a return pipe 48 from the radiator to the casing 34.

40 The refrigerant piping connections are preferably all made up with brazed or soldered joints to eliminate detachable fittings throughout the system, as it has been found that such fittings sometimes work loose or 45 are tampered with and any leakage of refrigeration or admission of air to the system results in lowered efficiency aside from the annoyance caused householders. By so 50 permanently joining the refrigeration piping it is not necessary to provide a large volume of excess refrigerant to make up for possible losses. The entire assembly of compressor, condenser and freezer are thus 55 permanently mounted on a framework comprising the upright member and the bracket and foot, the entire unit so formed being readily removed from the refrigerator box should servicing be required. As so removed, all the 60 parts are still coupled under operative conditions so that the operation of the entire unit can be observed to determine the need of 65 adjustments. A further advantage of this permanent assembly resides in the prevention of unauthorized tampering, as the brazed joints 70 form an effective deterrent to disassembly.

It will thus be seen that I have provided an improved and self-contained refrigerating unit particularly adapted to household use because of its compactness and the ease of removal and replacement of the entire operating mechanism as a unit. 70

I am aware that many changes may be made, and numerous details of construction may be varied through a wide range without departing from the principles of this invention, and I therefore do not purpose limiting the patent granted hereon, otherwise than necessitated by the prior art. 75

I claim as my invention:

1. A domestic refrigerating unit comprising 80 a refrigerator casing having a compartment therebeneath with rear openings into both the casing and the compartment, a closure for said opening into the casing, a freezer unit mounted thereon, a channeled connecting member secured to said closure and extending downwardly behind said compartment, a compressor and condenser unit in said compartment, and supporting means attached to said connecting member for 85 mounting said compressor and condenser unit in fixed relationship with the closure and freezer unit. 90

2. A domestic refrigerating unit comprising 95 a refrigerator casing having a compartment therebeneath with rear openings into both the casing and the compartment, a closure for said opening into the casing, a freezer unit mounted thereon, a channeled connecting member secured to said closure and 100 extending downwardly behind said compartment, a compressor and condenser unit in said compartment, supporting means attached to said connecting member for mounting said compressor and condenser unit in fixed relationship with the closure and freezer unit, and permanent piping connections from said freezer to said compressor and condenser unit, said piping being positioned in 105 the channel member. 110

3. A domestic refrigerating unit comprising 115 a refrigerator casing having a compartment therebeneath with openings into both the casing and the compartment, a closure for said opening into the casing, a freezer unit mounted thereon, a channeled connecting member secured to said closure and extending downwardly behind said compartment, a compressor and condenser unit in 120 said compartment, and supporting means attached to said connecting member for mounting said compressor and condenser unit in fixed relationship with the closure and freezer unit. 125

4. A refrigerating unit comprising a refrigerator body having a refrigerating compartment superimposed upon a compartment for the mechanical refrigerating apparatus and rearward openings formed in both compartments, a channeled framework extend- 130

ing up the back of the body and detachably secured thereto, a closure for the refrigerating compartment opening secured to said framework, a freezer unit mounted on the 5 inner face of said closure, a horizontal bracket secured to the framework, a mechanical refrigerating apparatus supported by said horizontal bracket within the lower compartment, and piping connecting said freezer 10 with said mechanical refrigerating apparatus and arranged in proximity to said framework to be protected from injury thereby.

5. A refrigerating unit comprising a refrigerator body having a refrigerating compartment superimposed upon a compartment for the mechanical refrigerating apparatus and openings formed in both compartments, a framework comprising a horizontal bracket extending into the lower compartment and 20 a channeled vertical member extending up the back of the body and detachably secured thereto, a closure for the refrigerating compartment opening secured to said vertical member, a freezer unit mounted on the inner 25 face of said closure, and mechanical refrigerating apparatus supported by said horizontal bracket within the lower compartment.

6. In a refrigerator, a refrigerator compartment, a freezing unit therein, a second compartment, a compressing and condensing unit therein, unitary supporting means connecting said freezing unit with said compressing and condensing unit, said supporting 30 means being detachably mounted on one wall of the refrigerator whereby the entire refrigerating apparatus is detachable as a unit from the refrigerator, and a supporting foot formed on said supporting means to 35 provide stability for the unit when removed from the refrigerator.

7. In a refrigerator, a refrigerator compartment, a freezing unit therein, a second compartment, a compressing and condensing unit therein, permanently sealed pipe connections between said freezer and said compressing and condensing unit, unitary supporting means connecting said freezing unit with said compressing and condensing 50 unit, said supporting means being detachably mounted on one wall of the refrigerator whereby the entire refrigerating apparatus is detachable as a unit from the refrigerator, and a supporting foot formed 55 on said supporting means to provide stability for the unit when removed from the refrigerator.

8. A refrigerating unit comprising a cabinet having a heat insulated upper compartment and a lower compartment, both compartments having openings at the rear thereof, an insulated closure for the upper compartment rear opening, a freezer unit within 60 said upper compartment mounted on said closure, mechanical refrigerating apparatus 65

within said lower compartment, conduits connecting said freezer unit and said refrigerating apparatus and a rigid frame having a channel therein for said conduits, said frame being secured to said closure and to said refrigerating apparatus and detachably secured to the rear wall of said cabinet to permit the removal from the cabinet of the entire operating mechanism as a unit. 70

9. A refrigerating unit comprising a cabinet having a heat insulated upper compartment and a lower compartment, both compartments having openings at the rear thereof, an insulated closure for the upper compartment rear opening, a freezer unit within 75 said upper compartment mounted on said closure, mechanical refrigerating apparatus within said lower compartment, piping extending along the outside of the rear wall of the cabinet through said closure to connect said refrigerating apparatus and said freezer unit, and a rigid frame secured to said closure and to said refrigerating apparatus and detachably secured to the rear wall of said cabinet to permit the removal 80 from the cabinet of the entire operative mechanism as a unit, said frame comprising an angular structural member serving also to protect the outside run of said piping. 85

In testimony whereof I have hereunto subscribed my name at Detroit, Wayne County, Michigan. 90
